UNITED STATES PATENT OFFICE.

GEORGE W. HORNE, OF NEW YORK, N. Y., ASSIGNOR OF ONE-FOURTH TO
BENJAMIN A. DARE, OF SAME PLACE.

RAILROAD-SWITCH MOVER.

SPECIFICATION forming part of Letters Patent No. 292,026, dated February 5, 1884.

Application filed August 7, 1883. (No model.)

To all whom it may concern:

Be it known that I, GEORGE W. HORNE, a subject of Her Majesty Queen Victoria, residing in New York city, in the county of New York and State of New York, have invented certain new and useful Improvements in Railroad-Switch Movers, of which the following is a specification.

My invention relates to that class of switch-point movers which adjust the points to suit either track, known as "low-stand" or "tumble-over."

My object is to devise a switch-point mover which can be operated with ease, and at the same time moving the switch-points accurately.

My further object is to provide a switch-mover which occupies less space and being less liable to get out of repair than those now in use, which will be hereinafter more fully explained, reference being had to the accompanying drawings, in which—

Figure 1 represents plan of switch-mover in connection with switch-points. Fig. 2 is enlarged end view, section *x* *x*, Fig. 1, with cover. Fig. 3 represents side elevation, section in *y* *y*, Fig. 2, with cover and lock. Fig. 4 represents end elevation of same when a higher stand is desired.

Similar letters refer to similar parts of the several views.

a represents outer shell or case; *b*, nut; *c*, movable sleeve; *d*, guide-rod; *e*, connecting-rod; *ff*, movable switch-points; *g*, fixed rail. In the case *a* is an annular spiral slot, *h*, into which is fitted a projection, *m*, on the outer surface of the nut *b*, and travels in the slot *h* in the same manner as a threaded bolt moves in its nut, the said nut *b* having projecting lugs or ears *n*, in which are holes to receive the guide-rod *d*, upon which the said nut and movable sleeve *c* move freely endwise. The movable sleeve *c* is retained in its relative position with the nut *b* by fitting between the projecting ears *n*. The connecting-rod *e* is attached to the sleeve *c* by lock-nuts, as shown. The nut *b* is revolved by arm *p*, attached to

same in the lug or projection *m*. By revolving the nut *b*, the projection on same travels in the slot *h*, and moves said nut endwise upon the guide-rod *d* in either direction the distance corresponding to the pitch or angle of the slot *h* in the case *a*, at the same time moving the sleeve *c* the same distance, which transmits its motion to the switch-points, and is locked by cover *k*, which protects it from dirt or snow.

The advantage of my improvement is that, the throw of the lever or arm being parallel with the track, I am enabled to place the mover close to the track, or between switch-points, if desired, whereas in the present system of using the crank the lever operates to and from the track, often occupying valuable space in its movements.

When it is desired to raise the stand or moving lever higher from the ground, I extend an upright brace or support upon the top of case *a*, having a hand-wheel and chain-drum attached thereto, the endless chain operating the nut in either direction, being applied to the drum and nut as shown in drawing Fig. 4.

As there are several different methods of applying an incline plane for the purpose of operating a switch-point, I do not therefore desire to restrict myself to the plan shown in the drawings, it only being my preferred manner of application.

To lessen the cost of construction, the rod *d* can extend through and beyond the case *a*, and be attached to the switch-points direct, the said rod moving freely endwise through the ends of the case *a*, and operated by the nut *b*, as above described. The sleeve *c* in this plan is firmly secured to the rod *d*, instead of moving freely thereon, which enables me to dispense with the connecting-rod *e* and lock-nuts.

What I claim, and desire to secure by Letters Patent, is—

1. In a switch-mover with a spiral slot or grooved channel, the rotating and traveling nut or hub *b*, with projecting lug *m* and pro-

truding lugs or ears *n*, embracing the sleeve *c*, and moving the same in either direction, substantially as and for the purpose described.

2. In a switch-mover, the case *a*, with spiral guide, nut, or hub *b*, with lugs *m*, protruding ears *n*, the adjustable sleeve *c*, and guide-rod *d*, the whole combined and operated in the manner described, for the purpose specified.

Signed at New York, in the county of New York and State of New York, this 6th day of July, A. D. 1883.

GEORGE W. HORNE.
